[57] CLAIM

The ornamental design for a latch mechanism, as shown and described.

DESCRIPTION

FIG. 1 is a top, front, and right side perspective view of a latch mechanism showing our new design;

FIG. 2 is a front elevational view thereof;

FIG. 3 is a top plan view thereof;

FIG. 4 is a bottom plan view thereof;

FIG. 5 is a rear elevational view thereof;

FIG. 6 is a right side elevational view thereof, the left side being a mirror image of that shown;

FIG. 7 is a top, front, and right side perspective view thereof, shown in an alternate position; and,

FIG. 8 is a front elevational view thereof, shown in an alternate position.

FIG. 1

FIG. 2

FIG. 3

FIG. 4

FIG. 5

FIG. 6

FIG. 7

FIG. 8
